UNITED STATES PATENT OFFICE.

JOHN Q. WALTON, OF WASHINGTON, DISTRICT OF COLUMBIA.

VALVE.

1,218,498.

Specification of Letters Patent.

Patented Mar. 6, 1917.

Application filed September 23, 1910. Serial No. 583,448.

To all whom it may concern:

Be it known that I, JOHN Q. WALTON, a citizen of the United States, residing at Washington, in the District of Columbia, 5 have invented new and useful Improvements in Valves, of which the following is a specification.

This invention relates to certain improvements in valves, and consists of several new 10 features of construction and combinations of parts substantially as hereinafter described and particularly pointed out in the subjoined claims. The improvements embodied in the present invention are particu- 15 larly but not exclusively applicable to steam stop valves and this application of the invention, which is preferred, accordingly is shown in the accompanying drawings and will be hereinafter described in detail with- 20 out however intending to restrict the invention, considered in its broadest aspects, thereto.

One of the important purposes of the present invention is to provide a means which 25 will prevent the danger of a ruptured steam connection by a water ram or hammer caused by the careless or sudden opening of a stop valve.

Another of the important purposes of the 30 present invention is to provide a valve which will operate automatically to cut off the flow of fluid, under pressure to the connections in the event of an accident in the latter.

There are other purposes of the invention 35 which will appear from the hereinafter description.

In accordance with the foregoing stated purposes the present invention embraces:

First, a stop valve comprising a main 40 valve and an auxiliary valve, arranged between a steam connection and a source of supply of steam to said connection; the auxiliary valve being provided with means for opening it manually and when so opened 45 establishing communication of the steam connection with the source of supply, so restricted however that the steam connection fills gradually, whereby the temperature of the steam connection is gradually raised and 50 the pressure in the steam connection is caused gradually to approach the pressure in the source of supply; the main valve be-

ing provided with means whereby it is automatically operated to uncover its port in the passage between the source of steam supply and the steam connection when the pressure in the latter has attained one predetermined with relation to that in the source of supply, the predetermined relative pressures at which the main valve shall automatically open being such that the main valve is opened only when the pressure in the steam connection has attained a degree which precludes all danger of there being a water ram or hammer, such as might result in a ruptured steam connection, produced when full communication of the steam connection with the source of steam supply is established.

Second: A stop valve comprising a main 70 valve and a manually-operated auxiliary valve arranged between a steam connection and a source of supply of steam to said connection, the auxiliary valve when opened serving to establish the previously-mentioned restricted communication of the steam connection with the source of supply and being so located with relation to the steam connection and stop valve that when it has been opened the steam connection and stop 75 valve will be thoroughly drained and the temperature thereof and pressure therein gradually raised before the admission of steam under full pressure is permitted.

Third: A valve arranged in the passage 85 between a connection and a source of supply of fluid, under pressure, and having means whereby it is automatically operated under control of predetermined relative pressures in the connection and source of supply, the 90 valve being held to its seat and serving to cut off communication of the connection with the source of supply, through the port within said seat, when the pressure in the connection is at a predetermined degree less 95 than that in the source of supply, whereby, as a consequence of any sudden lowering of the pressure in the connection, such as would be caused, for example, by an accident to the latter, the valve will be instantaneously 100 closed by the preponderating pressure on the side of the valve presented toward the source of supply, thereby wholly eliminating any dangers to life and property which may ex-

ist from a burst connection between the time the break occurs and the time the valve is manually closed.

The invention further consists in certain 5 peculiarities in the construction and arrangement of parts and in certain novel combinations of elements substantially as hereinafter described and particularly pointed out in the subjoined claims.

10 In the accompanying drawings there are illustrated several slightly different forms of stop valves to exemplify what is now regarded as the best embodiments of the present invention. It is to be understood, however, that the invention considered in its 15 broader aspects is not restricted to these particular embodiments and that changes may be made therein without departing from the spirit of the invention, or the scope of the 20 subjoined claims. It, further, should be understood that the particular illustrated embodiments have several important advantages over other means capable of carrying 25 into practice the fundamental purposes of the invention hereinbefore particularly named, and for this reason said particular embodiments are specifically made the subject matter of some of the subjoined claims.

15 In the drawings:

30 Fig. 1 is a view partly in elevation and partly in section of one form of stop valve embodying the present improvements, showing the parts in the position they occupy to hold the valve against being accidentally 35 opened.

Fig. 2 is a section on the line 2—2 of Fig. 1.

Fig. 3 is a section on the line 3—3 of the same.

40 Fig. 4 is a view similar to Fig. 1 of a slightly different form of valve embodying my improvements.

Fig. 5 is a similar view of another form of valve embodying the present improvements.

45 Fig. 6 is a section on the line 6—6 of Figs. 4 and 5.

Fig. 7 is a detail view showing the relative position of parts when adjusted for operation of the valve.

50 Fig. 8 is a detail view of a stop for supporting parts when the valve is being overhauled.

Similar characters of reference denote corresponding parts in all the views.

55 In all the different forms of the present valve, herein exemplified, there is a body, marked 10, which is provided with a chamber, marked 11, having an outlet 12, and an inlet 13. This inlet is controlled by a valve, 60 marked 14, whose seat is marked 15. When this valve 14 is fully opened, the steam pipes connected with the outlet 12 are thrown into full communication with the boiler, marked A. If this occurs when the 65 body 10 or the steam pipes are cold, or if,

through carelessness or otherwise, the valve is opened quickly, instead of slowly and gradually, a water hammer or ram results, with consequent danger of a ruptured steam connection, and when a ruptured steam connection occurs the communication between said connection and the source of steam supply must be instantaneously cut off, to save men in the immediate vicinity of the rupture from being scalded, and also to save possible dangerous boiler explosion. To eliminate all liability of a ruptured steam connection made possible by the use of a valve which can be fully opened or opened too widely before the steam connection is in condition safely to receive full, or approximately full, steam pressure and which when so opened will permit the steam to be supplied at such pressure, there is provided an auxiliary steam connection from the boiler, whereby the steam initially enters the pipes in quantity such as to cause a gradual heating thereof, and the valve 14 is maintained upon its seat until the steam pipes have become thus heated. The valve 14 is provided with means whereby it is then automatically opened to permit the full pressure of the steam from the boiler to enter the steam connection.

70 The auxiliary steam connection hereinbefore referred to preferably comprises a chamber or channel 16 which communicates with the chamber 11 and is provided with a manually-operable valve 17 by which it may be opened and closed. As one of the 75 important factors in the total elimination of water hammer or ram when steam is admitted to the steam connection the auxiliary valve 17 is so arranged that when it has been 80 opened any water in the steam connection and, preferably, also in the body 10, will be automatically drained by gravity from said connection and body while steam of small 85 volume is being admitted thereto, thereby, further, eliminating the necessity of draining 90 the steam connection by a separate operation before admitting steam to the same.

95 The operating means for the valve 14 may comprise both a spring 18, and a differential piston 19, mounted on the valve stem 20, as shown in Fig. 4, or the differential piston may be omitted, as shown in Fig. 1, or the spring may be omitted, as shown in Fig. 5; or in fact other than the 100 means herein illustrated, capable of holding the valve 14 to its seat until a predetermined pressure or temperature has been 105 reached in the steam connections, or of opening said valve when such predetermined pressure or temperature has been attained, may be resorted to, without departing from the spirit of the invention as defined by some of the hereto subjoined 110 claims.

115 Having thus, in a general way, set forth 120

some of the main or most important features of the present invention, I will now particularly describe the embodiments thereof illustrated to exemplify its most 5 satisfactory forms.

The body 10 may be suitably mounted, as shown, on a boiler A, or in any other suitable location without departing from the spirit of the invention. This body in the 10 forms shown in Figs. 1 and 4 is provided with a cover or bonnet, marked 21, from which extends a frame, preferably of open formation. This frame is of a length adapted to contain the spring 18, and preferably is 15 composed of spaced arms 22 relatively disposed to form a yoke having a bearing 23 at its end remote from the bonnet.

Within this frame are spring abutments 24 and 25 which are relatively adjustable to 20 regulate the power of the spring. In the exemplified arrangement both abutments are adjustable. The abutment 24 is shown as provided with a sleeve 26 which is slidably fitted to the valve stem 20. This sleeve 25 is externally threaded and engaged by an adjusting nut, marked 27, which is mounted in the bearing 23 and has a hand wheel 28 for adjusting it. This nut is held against longitudinal movement, preferably by having a flange 27^a which engages the inner end of the bearing 23, while its hand wheel 28 bears against the outer surface of the bearing. For preventing rotative movement of the abutment 24 and guiding it in 30 its reciprocatory movement, it is preferably provided with radially-arranged arms 24^a suitably engaged with the frame. In the illustrated embodiment, the arms 22 of said frame are provided with ribs or flanges 22^b 35 which extend longitudinally thereof and are received by recesses 24^b in the arms, respectively, as shown best in Fig. 3.

The lower abutment, 25, is similarly shown as provided with radial arms, 25^a, 40 whose ends engage the ribs or flanges 22^b and serve to guide the valve stem in its reciprocatory movement. The ribs or flanges 22^b are provided with cut away portions, marked 22^c, for convenience in assembling 45 and disassembling the parts.

It will now be seen that the spring 18 50 may be placed in compression by the abutment 24 and that this compression may be variably regulated by adjustment of the abutment 24. It will also be apparent that the valve is automatically opened by the spring, when the power of the latter, added to the pressure of the steam acting on the 55 valve in the same direction, overcomes the force of the steam acting contrary thereto. Hence, it becomes possible so to co-relate the forces that the valve will be maintained in closed position until the valve body has 60 become heated sufficiently to avoid a water ram or hammer, all danger of which will

be completely avoided when the spring is set to open the valve when the steam pressure in the steam connection and the body of the valve is practically equal to that in the boiler and the pipe or connection.

In all the illustrated embodiments of the invention, the valve stem 20 is made hollow and formed to provide the hereinbefore referred to chamber or channel 16, and the latter has communication with the chamber 11 through ports 29 in said valve stem. The auxiliary valve 17, by which communication of the chamber 11 with the boiler A is controlled, is shown as provided with a stem 30 which extends longitudinally 75 through the valve-stem 20 and has a hand-wheel 31 for adjusting it to and from its seat 32 formed upon the valve 14.

The seat 15 for the valve 14 is preferably formed on a hollow member 33 separate 80 from the body 10 and threaded or otherwise removably secured to the latter, as shown. The inlet 13 hereinbefore referred to is in this member. A spider, marked 34, or other suitable means, preferably integral with 85 the member 33, is provided as a guide for the valve-stem 20. A bushing 35 mounted on the cover or bonnet, serves as a packing and guide for the valve-stem 20 intermediate of the length of the latter.

Upon the valve stem 20 there is adjustably mounted a stop, marked 37, to limit the opening movement of the main valve. This stop preferably has a hand-wheel 37^a for adjusting it.

Attention is called to the fact that when the parts are in the position shown in Fig. 1, the stop 37 is in contact with the upper end of the sleeve 26. This is the position of the parts when the valve is not in use and by reason thereof the main valve is positively fixed against being opened by pressure accidentally applied to its stem. In this position the parts are left when a boiler associated with the stop valve is cut out of 95 line.

As a preliminary to the operation of the valve, the hand wheel 28 is turned to withdraw the sleeve 26 from its contact with the stop 37 and to place the spring under 100 compression. This position of the parts is indicated in Fig. 7. The stop 37 is next adjusted, if necessary, to determine the extent of opening movement of the main valve 14. In practice, it is preferred to turn the hand 105 wheel 28 until the spring has been compressed sufficiently to open the main valve automatically when the pressure in the main body of the valve and the steam connection is practically equal to that in the boiler.

The parts having thus been set and steam pressure being on the boiler and all closed, the hand wheel 31 is turned to open the auxiliary valve 17 and steam enters the 110 chamber 16 and thence passes into the body 130

of the valve and the steam connection. As soon as the pressure in the body of the valve and the steam connection reaches the point predetermined at which the main valve 14 shall be opened, said main valve will be automatically forced from its seat the distance determined by the stop 37 which, moving with said valve, will come in contact with the sleeve 26, or some other suitable part which may be provided to coöperate with said stop to restrict the opening movement of the main valve. During its movement, said main valve is guided by the engagement of the arms 24^a and 25^a with the webs or flanges 22^b of the frame 22.

In the event that rupture of the steam connection occurs, or some other accident takes place whereby the flow of steam is suddenly increased the pressure of the steam on the back of the main valve will overcome the compression of the spring, and the main valve instantly will close and cut the boiler out of line.

A clamp collar marked 39 is fitted to a recess turned in the valve stem 20 above the guide 34, for supporting the weight of the main valve and stem when overhauling the same, and a perforated cap, marked 40, is fitted to a threaded boss on the main valve for supporting the weight of the auxiliary valve 17 and its stem under similar conditions.

If it is desired to convert this automatic safety stop valve into an ordinary screw stop valve, this may be done by adjusting a stop 41, which is shown as a nut or sleeve threaded upon the stem 20 between the abutments 24 and 25, until it bears against the abutment 24. When this has been done the sleeve 26 is locked between the stops 37 and 41 and thereby fixed to the valve stem 20, whereby the latter may be raised or lowered by the hand wheel 28, the sleeve, stops 37 and 41 and the valve stem moving as a unit.

If the spring 18 weakens, the abutment 25 may be adjusted nearer to its companion, 24, to compensate for such weakness.

If preferred, a differential piston may be mounted on the valve stem 20, either to supplement the spring 18, as shown in Fig. 4 or as a substitute for said spring, as shown in Fig. 5. When this piston is employed the valve body is formed or provided with a chamber 100, here shown by extending the body outward beyond the plane of the outlet 12. The piston here shown comprises an annulus 101 provided with radially-arranged arms 102 extending thereto from a bearing 103 which preferably is threadably engaged with the valve stem 20. This piston thus has openings through which the chamber 11 at one end of the piston has communication with the space or chamber at the other end thereof. A greater area of piston surface for the steam to act on in opening the valve

is provided by enlarging the diameter of the corresponding end thereof, as shown. Preferably, the piston is beveled toward said end to lighten its weight, as shown at 104. The outer circumferential wall of the annulus engages the inner wall of the piston chamber, packing rings 105 being preferably interposed between the two in order to make a steam-tight fit which will permit wear to be compensated for. 106 designates a relief port which, in practice, may be provided with a relief cock, not shown. A part of the steam initially admitted by the auxiliary valve 17 flows through the openings between the arms 102 and acting upon the upper end of the piston and against the beveled surfaces 104 tends to force the piston toward its valve-opening position. This tendency, however, is counteracted by the boiler pressure acting in the contrary direction on the main valve and also, to a comparatively slight extent, by the pressure within the chamber 11 acting against the lower face of the piston, until the latter pressures are overcome by the raising of the pressure within the chamber 11 to that at which it is intended the main valve shall open.

In event that the spring 18 is dispensed with, the yoke or frame can be made materially shorter than before, such a frame being shown in Fig. 5 and marked 122.

In the latter form of the device the sleeve 26, nut 27, hand wheel 28 and stop 41, all of which are shown in Fig. 5 (as well as the abutment 25 which is not shown in said figure) also may be omitted, but it is considered preferable to employ the illustrated parts in order that the valve may be operated manually for testing purposes, this being done by adjusting the stop 41 into contact with the sleeve 26, as before described.

It will be apparent that by means of the auxiliary valve the steam connections above it and also the chamber 11 may be drained as well as gradually warmed up.

It will be seen that the herein exemplified embodiments of my invention are well calculated to cause a gradual heating of the steam connections and body of the stop valve, or the gradual equalization of the pressure between said body and the steam connection and the boiler, before said body and connections are subjected to full boiler pressure, and, moreover, affords provision for the preheating of the connections and valve body by the auxiliary connections, whether the main valve is operated automatically or its operating means are adjusted for manual operation. It will also be seen that provision is made for locking the main valve against its being accidentally opened. Further, it will be seen that provision is made for variably determining the extent of the automatic opening of the main

valve: and that these several important features are embodied in a construction of simple, durable and practicable nature, whose parts are not liable to get out of order, may

- 5 be readily assembled and relatively adjusted, and readily disassembled for cleaning purposes and for renewals. Again, it will be noted that while it has herein been stated that the auxiliary valve 17 is opened manu-
 10 ally by turning the hand wheel 31, it is quite practicable to open it simultaneously with the adjustment of the stop 37 to determine the extent of opening of the main valve; for example, by setting the hand wheel 31
 15 until the shoulder 31^a on the sleeve 31^b thereof is in the path of the stuffing-box casing 31^c, which moves with the hand wheel 37^a.

It will further be noted that when the 20 primary supporting means for the valve stem 20, which primary means are composed of the elements by which the valve stem is held against dropping through the casing or valve body when the parts are assembled, 25 are removed, as they are in the overhauling of the valve, the valve stem unless otherwise supported would drop into the boiler or into the steam pipe, upon either of which it may be mounted in practice. The sec-
 30 ondary supporting means composed of the stop 39 and the spider or support 34, in the exemplified embodiment, now becomes operative to support the valve stem, the latter dropping until its stop 39 rests upon the
 35 spider.

Again, it will be noted that the auxiliary valve is seated at the lowest part of the structure whereby thorough draining of the body, and the connections above said valve 40 is provided for, and that the main valve is located at the lowest part of the body and outside of the latter and in position to enter the boiler or pipe from which the body receives its supply of steam, whereby no 45 steam will enter any part of the body and said body is relieved of steam pressure when the valves are closed. Further, it will be noted that the auxiliary valve may be moved from or to its seat wholly independently of 50 the main valve, and hence may be opened and closed at any position of the latter, or may be set to close with the main valve.

Having now described the invention what I believe to be new and desire to secure by 55 Letters Patent, is:—

1. Means for controlling communication between a source of steam supply and a steam connection, the said means comprising a main valve and an auxiliary valve, 60 each having a stem, said valves severally controlling such communication, the auxiliary valve having means independent of the main valve stem whereby it is manually operated and being movable with and relatively to the main valve and adapted when

fully open to admit steam to the connection in volume such as to cause a gradual increase in the temperature of and pressure within the latter, the main valve being arranged to be held to its seat until a predetermined pressure has been reached in the connection and adapted when fully opened to admit steam under full pressure to said connection and means having connection with the stem of the main valve and oper-
 70 able to open the same.

2. Means for controlling communication between a source of steam supply and a steam connection, the said means comprising a body having an inlet to the source of steam-supply and an outlet to the connection, a main valve and an auxiliary valve each having a stem, said valves severally controlling communication between the inlet and the outlet, the auxiliary valve being 85 movable with and relatively to the main valve and having means independent of the main valve stem whereby it is manually moved from its seat and being adapted when fully open to admit steam to the outlet in a quantity such that the temperature of and pressure within the connection will be gradually raised, the main valve being subject to and held to its seat by the pressure of steam at the inlet side of the body until a predetermined pressure has been reached in the connection and adapted when fully opened to admit steam under full pressure to said connection, and means having connection with the stem of the main valve for automatically opening said valve when said predetermined pressure is reached.

3. Means for controlling communication between a source of steam supply and a steam connection, the said means comprising a body having an inlet to the source of steam-supply and an outlet to the connection, a main valve and an auxiliary valve severally controlling communication between the inlet and the outlet, the auxiliary 105 valve being movable with and relatively to the main valve and having means whereby it is manually moved from its seat and being adapted when fully open to admit steam to the outlet in quantity such that the temperature of and pressure within the connection will be gradually raised, the main valve being subject to and held to its seat by the pressure of steam at the inlet side of the body until a predetermined pressure has been reached in the connection and adapted 110 when fully opened to admit steam under full pressure to said connection, and means co-operating with the pressure at the outlet side of the body for automatically opening 115 the main valve when the two pressures have reached a predetermined relation.

4. Means for controlling communication between a source of supply and a connection, the said means comprising a main 120

- valve, and an auxiliary valve and their seats, severally controlling such communication, the seats of the valves having different areas, the port of the main valve-seat being of larger area than the auxiliary valve-seat, the auxiliary valve being movable with and relatively to the main valve and having means whereby it is manually operable and means for automatically opening the main valve when the pressure in the source of supply and connection have reached a predetermined relation.
5. A stop valve comprising a body having a steam inlet and a steam outlet, a main valve for controlling the flow of steam from the inlet to the outlet, means operable to open the main valve automatically when a predetermined pressure on the outlet side of said body has been obtained, and an auxiliary means including a valve arranged to be seated upon the main valve and movable relatively thereto adapted to permit this predetermined pressure to be gradually obtained.
10. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, means operable to open the valve automatically when a predetermined pressure on the outlet side of the body has been obtained, and an auxiliary means adapted to permit this predetermined pressure to be gradually obtained, said auxiliary means comprising a passage leading to the intermediate chamber and a manually operable valve for controlling said passage.
15. A valve comprising a body having an inlet and an outlet, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.
20. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, means operable to open the valve automatically when a predetermined pressure on the outlet side of the body has been obtained, and an auxiliary means adapted to permit this predetermined pressure to be gradually obtained, said auxiliary means comprising a passage leading to the intermediate chamber and a manually operable valve for controlling said passage.
25. A valve comprising a body having an inlet and an outlet, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.
30. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, means operable to open the valve automatically when a predetermined pressure on the outlet side of the body has been obtained, and an auxiliary means adapted to permit this predetermined pressure to be gradually obtained, said auxiliary means comprising a passage leading to the intermediate chamber and a manually operable valve for controlling said passage.
35. A valve comprising a body having an inlet and an outlet, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.
40. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.
45. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.
50. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.
55. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.
60. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.
65. A valve comprising a body having an inlet, an outlet and an intermediate chamber, a main valve for controlling the flow of fluid, under pressure, from the inlet to the outlet, said valve being arranged to open in a direction opposed to that of the flow of the fluid, means for adjustably regulating the amount of its opening, a spring connected with the said valve and adapted to open the same when a predetermined pressure has been obtained on the outlet side of said body, and means whereby such predetermined pressure is obtained gradually.

mined pressure is obtained gradually, comprising an auxiliary channel leading to the intermediate chamber and provided with a manually-operable valve for controlling it.

9. A valve, comprising a body having an inlet and an outlet, a main valve for controlling the flow of fluid under pressure from the inlet to the outlet, a differential piston and a spring connected with the said valve and adapted to open the same when a predetermined pressure has been obtained on the outlet side of said body, and means whereby such predetermined pressure is obtained, gradually.

10. A valve comprising a body having a chamber, an inlet and an outlet, a main valve controlling the flow of fluid, under pressure, from the inlet to the outlet, a differential piston having connection with said valve and mounted in said chamber, said piston having an opening for the passage of fluid, under pressure, from one of its sides to the other, and being adapted to open said valve when a predetermined pressure has been obtained on the outlet side of said body, and means whereby such predetermined pressure is obtained, gradually.

11. A valve comprising a body having a chamber, an outlet in open communication with said chamber and an inlet, a main valve and an auxiliary valve and their seats, interposed between the chamber and the inlet and severally controlling the admission of fluid, under pressure, to the former, the auxiliary valve being movable with and relatively to the main valve, the port in the seat for the auxiliary valve being of less area than the main-valve seat port, means for opening the auxiliary valve manually without affecting the main valve and means whereby the main valve is opened automatically when the pressure in the chamber reaches one having a predetermined relation to that at the inlet side of the main valve.

12. A valve comprising a body having a chamber, an outlet in open communication with said chamber and an inlet, a main valve and an auxiliary valve and their seats, interposed between the chamber and the inlet and severally controlling the admission of fluid, under pressure, to the former, the auxiliary valve being movable with and relatively to the main valve, the port in the seat for the auxiliary valve being of less area than the main valve-seat port, means for opening the auxiliary valve manually without affecting the main valve and a spring operatively connected with the main valve and serving to open the same automatically when the pressure in the chamber reaches one having a predetermined relation to the pressure at the inlet side of the main valve.

13. A valve comprising a body having a chamber, an outlet in open communication with said chamber and an inlet, a main

valve and an auxiliary valve and their seats, interposed between the chamber and the inlet and severally controlling the admission of fluid, under pressure, to the former, the port in the seat for the auxiliary valve being of less area than the port in the main valve-seat, means for opening the auxiliary valve manually without affecting the main valve, a differential piston mounted in the chamber and a spring, said piston and spring being operatively connected to the main valve and serving to open the same automatically when the pressure in the chamber reaches one having a predetermined relation to the pressure at the inlet side of the main valve.

14. A stop valve having a body provided with a steam chamber, a steam outlet in open communication with said chamber and a steam inlet, a main valve interposed between the steam chamber and the inlet, said valve having a hollow stem with a lateral outlet port opening into the steam chamber and an inlet port toward the source of supply of steam, an auxiliary valve having its seat adjacent to said inlet port, means independent of the main valve stem for manually opening the auxiliary valve to admit steam to the interior of the steam chamber for preheating the body and the connections connected to the outlet, and means for opening the main valve when a predetermined pressure has been attained in said connection.

15. A valve comprising a body having a chamber, an outlet in open communication with said chamber and an inlet, a main valve interposed between the chamber and the inlet, said valve having a hollow stem with a lateral outlet port opening into the chamber and also having an inlet port, an auxiliary valve having its seat adjacent to the inlet port in the main valve, means for manually opening the auxiliary valve to admit fluid, under pressure, to the interior of the chamber and means for automatically opening the main valve when a predetermined pressure has been obtained in said chamber.

16. A valve, comprising a body, a reciprocatory valve, its stem, a pair of abutments, one of said abutments being fixed on the stem and the other slidably mounted on the stem, means connected with the slidable abutment for preventing rotative movement of the same on the stem, means connected with the fixed abutment for preventing rotative movement of the stem, a spring mounted between the abutments and tending to move the valve and stem in one direction, and means for moving the valve and stem in opposition to the spring, the latter means comprising a sleeve connected to the slidable abutment, a nut threaded upon the sleeve and held against longitudi-

nal movement and an adjusting device for the nut.

17. A valve, comprising a body, a reciprocatory valve, its stem, a frame having a bearing, a spring tending to open the valve, an abutment for the spring, having a sleeve slidably engaged with the stem and a part engaged with the frame, the interengaging parts of the abutment and frame being adapted to prevent rotative movement of the former, a nut mounted in said bearing and threaded upon said sleeve, an adjusting device for the nut, said nut being held against longitudinal movement, and a second abutment for the spring fixedly secured to the stem and provided with a part which engages the frame and is held against rotative movement thereby.

18. A valve, comprising a body having an inlet and an outlet, a valve for controlling the inlet, means operative to open said valve automatically when a predetermined pressure has been obtained in the body, auxiliary means arranged to permit this predetermined pressure to be obtained, and adjustable means for variably regulating the extent of the opening movement of said valve, comprising a stop adjustably mounted on the stem of the valve and means adjustable to engage said stop to prevent accidental opening of the valve.

19. A valve, comprising a body having an inlet for the admission of fluid under pressure and also having an outlet for the fluid, a valve for controlling the inlet, a bypass of area less than the area of the inlet through which the fluid may enter from the source of supply to the outlet side of the valve, a spring coöperating with the pressure of the fluid in the body to open the valve automatically when the latter pressure has attained a predetermined relation to that of the source of supply, abutments for the spring, one of said abutments being connected with the valve, a sleeve connected with the other abutment, and means for adjusting the sleeve to put stress on the spring.

20. A valve, comprising a body having an inlet and an outlet, a valve for controlling the inlet, a valve stem, a spring, abutments for the spring, one of said abutments being connected with the valve stem and the other adjustably mounted with relation thereto and having a sleeve, and a stop on the valve stem adapted to be engaged by the sleeve, said sleeve being adjustable to a place where it coöperates with said stop to prevent any movement of the valve from its seat and from said place to put stress on the spring, and said stop being adjustable relatively to the stem and sleeve.

21. A valve, comprising a body having an inlet and an outlet, a valve subjected to fluid pressure tending to hold it to its seat,

means operative to open said valve automatically when a predetermined pressure has been obtained in the outlet, means whereby such predetermined pressure may be obtained, and mechanical means for holding said valve to its seat, adjustable into and out of operative relation with the valve.

22. Means for controlling communication between a source of supply of fluid, under pressure, and a connection, the said means comprising a valve having an inlet for connection with said source of supply and an outlet to the connection, a main valve for controlling the inlet, means controllable to admit fluid, under pressure, to the outlet side of the main valve in volume adapted to raise the pressure in the body of the stop valve gradually and means for opening the main valve automatically when the pressure in the body of the valve has attained a predetermined relation to that in the source of supply, the latter means comprising a spring having connection with the main valve, and means adjustable to put variable stress on said spring.

23. Means for controlling communication between a source of supply of fluid, under pressure, and a connection, the said means comprising a valve having an inlet for connection with said source of supply and an outlet to the connection, a main valve for controlling the inlet, means controllable to admit fluid, under pressure, to the outlet side of the main valve in volume adapted to raise the pressure in the body of the valve gradually and means for opening the main valve automatically when the pressure in the body of the valve has attained a predetermined relation to that in the source of supply, the latter means comprising a spring having connection with the main valve, means adjustable to put variable stress on said spring, and a stop movable with the main valve, said stop and means being so correlated that they are adapted co-operatively to prevent movement of the main valve from its seat when relatively adjusted to a certain position.

24. A valve comprising a body having an inlet and an outlet, a valve, means operative to open said valve automatically when a predetermined pressure has been obtained in the outlet, means through which said pressure can be obtained, and adjustable means for rendering the automatic means inoperative or operative, at will without interfering with the operation of the main valve.

25. A valve comprising a body having an inlet and an outlet, a valve, means operated to open said valve automatically when a predetermined pressure has been obtained in the body, means through which said pressure can be obtained, adjustable means for rendering the automatic means inoperative and a manually operable means for ad-

justing the valve when the automatic means are inoperative.

26. A valve, comprising a body, having an inlet and an outlet, a valve, its stem, means operative to open said valve automatically when a predetermined pressure has been obtained in the body, means through which said pressure can be obtained, a hand wheel, a sleeve slidably mounted on the valve stem, means whereby the hand wheel is prevented from moving longitudinally and has threaded engagement with the sleeve, and means adapted to lock the sleeve to and release it from said stem.

27. A valve, comprising a body having an inlet and an outlet, a valve, its stem, a spring operative to open said valve automatically when a predetermined pressure has been obtained in the body, means through which said pressure can be obtained, a hand wheel, a sleeve slidably mounted on the valve-stem and having means whereby it puts stress on the spring, means whereby the hand wheel is prevented from moving longitudinally and has threaded engagement with the sleeve for adjusting the latter, and means adapted to lock the sleeve to and release it from said stem.

28. A valve comprising a body having an inlet and an outlet, a valve, its stem, means connected with said stem for opening the valve automatically when a predetermined pressure has been obtained in the body, means through which said pressure can be obtained, a hand wheel, a sleeve slidably mounted on the valve-stem, a stop mounted on the stem at one end of the sleeve, a stop adjustably mounted on the stem at the other end of the sleeve, said stops being adapted to clamp the sleeve between them, and means whereby the hand wheel is prevented from moving longitudinally and has threaded engagement with the sleeve.

29. A valve, comprising a body having an inlet and an outlet, a main valve, means operable to open the main valve automatically when a predetermined pressure in said body has been obtained, an auxiliary valve adapted to permit this pressure to be obtained gradually, adjustable means for determining the extent of opening movement of the main valve and means whereby the auxiliary valve is opened by adjustment of said adjustable means.

30. A stop valve, comprising a body having a steam inlet and a steam outlet, main and auxiliary valves, the main valve having a port which opens directly into the body near the steam inlet and through which steam is admitted in quantity adapted to heat the body and steam connection gradually, and the auxiliary valve being seated in the main valve and controlling said port, said main valve having a hollow stem and

the auxiliary valve being provided with a stem extending through the stem of the main valve and means applied to each stem for operating the valves independently of each other.

31. A stop valve, comprising a body having a steam inlet and a steam outlet, main and auxiliary valves, the main valve having a port which opens directly into the body 10 near the steam inlet and through which steam is admitted in quantity adapted to heat the body and steam connection gradually, and the auxiliary valve being seated in the main valve and controlling said port, 15 said main valve having a hollow stem and the auxiliary valve being provided with a stem extending through the stem of the main valve, a hand wheel mounted on the stem of the auxiliary valve outside the stem 20 of the main valve and means applied to the stem of the main valve whereby the same may be opened manually.
32. A stop valve, comprising a body having a steam inlet and a steam outlet, main 25 and auxiliary valves, the main valve having a port which is in communication with the steam outlet and through which steam is admitted in quantity adapted to heat the body and steam connection gradually, and the auxiliary valve being seated in the main 30 valve and controlling said port, said main valve having a hollow stem and the auxiliary valve being provided with a stem extending through the stem of the main valve, 35 a hand wheel mounted on the stem of the auxiliary valve outside the stem of the main valve and means whereby the main valve is opened automatically when a predetermined pressure of steam has been obtained in the body.
33. A stop steam valve comprising a body 40 having a steam inlet at its lowest part and also having a steam outlet, a main valve for closing said inlet, said main valve being provided with an inlet port which is in 45 open communication with the steam outlet when said port is uncovered, and an auxiliary valve for said port, the auxiliary valve being movable relatively to the main valve, 50 whereby the body is thoroughly drained and steam in comparatively small volume is admitted to the outlet when the auxiliary valve is opened.

34. A stop valve comprising a body having a steam inlet at its lowest part and also 55 having a steam outlet, a main valve for closing said inlet, said main valve being provided with an inlet port which is in open communication with the steam outlet when said port is uncovered, and an auxiliary 60 valve for said port, the auxiliary valve being movable relatively to the main valve, whereby the body is thoroughly drained, and steam in comparatively small volume is admitted to the outlet when the auxiliary valve 65 is opened and means for automatically opening the main valve when the pressure of steam admitted through the port in the main valve attains a predetermined relationship with that on the outer side of the main 70 valve.

35. In combination with a steam boiler, a stop valve comprising a body mounted on said boiler and having an inlet port, a downwardly-opening valve for controlling said 75 port, located outside said body in position to enter the boiler, an auxiliary inlet port, an auxiliary valve for closing the latter port, means for manually operating the auxiliary valve, the valve body also having 80 a steam outlet and a passage through which the auxiliary and main inlet ports have communication with its said outlet, and means whereby the main valve is automatically 85 opened and closed under control of predetermined variations in pressures in the body.

36. A valve comprising a body having an inlet and an outlet, a main valve for controlling the flow of fluid under pressure 90 from the inlet to the outlet, means operable to open the main valve automatically when a predetermined pressure on the outlet side of the body has been obtained, and an auxiliary means including a valve arranged to be 95 seated upon the main valve and movable relatively thereto adapted to permit this predetermined pressure to be gradually obtained.

In testimony whereof I have hereunto set 100 my hand in presence of two subscribing witnesses.

JOHN Q. WALTON.
